D. J. Craig,
ATTORNEY.

UNITED STATES PATENT OFFICE

EDWARD E. DETTELBACH, OF LOS ANGELES, CALIFORNIA

ORTHOPEDIC DEVICE

Application filed July 7, 1930. Serial No. 465,813.

This invention relates to improvements in orthopedic devices.

The general object of the invention is to provide an improved device adapted to be applied to a shoe for correcting foot ailments.

Another object of the invention is to provide an attachment for a shoe by means of which pressure may be applied to the various portions of a foot.

10 A further object of the invention is to provide a device for applying pressure on a foot from the exterior of a shoe.

15 A still further object of the invention is to provide a foot correction device for attaching to shoes having adjustable means for applying pressure on the foot.

20 Other objects and the advantages of this invention will be apparent from the following description taken in connection with the accompanying drawings wherein:

Fig. 1 is a bottom plan view of a shoe showing my improved device operatively positioned thereon.

25 Fig. 2 is an enlarged section taken on line 2—2 of Fig. 1.

Fig. 3 is an enlarged section taken on line 3—3 of Fig. 1.

Fig. 4 is a section taken on line 4—4 of Fig. 3.

29 Fig. 5 is an enlarged section taken on line 5—5 of Fig. 1.

Fig. 6 is a view similar to Fig. 1 showing the manner in which my improved foot correction device may be made in sectional parts, 35 and

Fig. 7 is an enlarged section taken on line 7—7 of Fig. 6.

Referring to the drawings by reference characters I have indicated a shoe generally 40 at 10 which includes a sole 12, a heel 13 and an upper 14. My improved device includes a metal border 15 and a plurality of pressure applying devices 16 and 17.

The border 15 is preferably made of a good 45 grade of spring steel and comprises a side flange 18, an inturned upper flange 19 and an inturned lower flange 20. The border 15 is shaped to conform to the shape of a shoe and when in position thereon the side flange 18 is adapted to engage the sides of the shoe sole

12 and the top flange 19 is adapted to engage the top of the sole which projects beyond the upper while the lower flange 20 is adapted to engage the bottom of the sole. The border 15 is preferably colored to match 55 the color of the shoe sole and the upper flange 19 is preferably provided with crimping as indicated at 21 to simulate the crimping of the last.

Various means may be used for securing 60 the border 15 in position, but I have shown the lower flange 20 as provided with opposed downwardly extending apertured lugs 22 adjacent the heel in the apertures of which I position a bolt 23 on which a nut 24 is provided.

The metal border 15 being made of spring metal does not appreciably impair the flexibility of the shoe but it does retain the shoe 70 in its correct shape by preventing spreading of the shoe.

In the lower flange 20 of the border 15 I provide a plurality of elongated apertures 75 25. When it is desired to raise one side of the sole of a shoe, rubber plugs 26 are positioned in the correct number of the apertures 25 to cause the sole of the shoe to assume the desired angle in walking.

The pressure applying devices 16 are made 80 of spring steel and constitute a plate body portion 27 having a depressed portion 28 intermediate the length thereof and countersunk apertures 29 adjacent each end. (See Figs. 1 and 5). The pressure device 16 is placed in the desired position on the sole of 85 the shoe and secured thereby by brads 30 before the border is placed on the shoe, thus the ends of the device 16 are covered by the bottom flange 20 of the border. When the device 16 is operatively placed in position on 90 the shoe the depression 28 bulges the sole of the shoe inwardly as shown in Fig. 5 thus applying pressure on the foot of the wearer.

One or more of the devices 16 may be used 95 and they may be placed in various positions and at various angles to apply pressure to the desired parts of the foot.

The device 17 is adapted to apply pressure 100 to the arch of the foot and as shown comprises a metal housing 32 having side flanges

33 which are adapted to be positioned between the under face of the shoe sole and the lower flange 20 of the border 15. Positioned in the housing 32 I provide an expansion member 34 which includes a lower portion 35 and an upper portion 36, each of which is provided with a mutilated thread to provide a tapered arcuate threaded recess 37.

Positioned in the recess 37 I provide a tapered threaded bolt 38 which includes a polygonal head 39. To apply pressure on the arch of a foot the expansion device 34 is placed in the desired position and the bolt 38 rotated to raise the upper member 36 thereby causing the sole of the shoe to bulge inwardly as shown in Fig. 3. Instead of using the expansion device 34 a piece of hard leather or similar material may be positioned in the housing 33 to apply a pressure to the arch if desired.

The border 15 may be used without the devices 16 and 17 and the apertures 25 and the rubber pads 26 may be omitted from the border if desired.

In Fig. 6 I have indicated generally at 40, 41 and 42 sections of metal borders which are similar to the border 15. When the border 15 is made in sections as shown in Fig. 6 it is only necessary to place a section on the shoe sole where it is desired to apply a local pressure instead of completely around the sole as shown in Fig. 1. The arch portion 42 of the sectional border in addition to the securing bolt 23 is provided with another securing member 43. The member 43 includes a flat piece of metal 44 which extends across the sole and the ends of which are adapted to be positioned between the shoe sole and the lower border flange 20. The member 44 has arms 45 and 46 pivotally secured thereto intermediate its length as indicated at 47. The free ends of the arms 45 and 46 are provided with pins 48 which are adapted to be positioned in apertures 49 provided in the flange 20 of the border and apertures 50 provided in the portion 44 of the fastening member.

From the foregoing description it will be apparent that I have provided a novel foot correction device which is simple in construction and efficient in use.

Having thus described my invention what I claim is:

1. In combination with a shoe including a sole, a pressure applying device, said device being made of a material of a greater hardness than said sole and engaging the outer surface of said sole, a depression intermediate the length of said device, said depression causing said sole to bulge inwardly and means to retain said device in position on said sole.

2. In combination with a shoe including a sole and a heel, a border, said border extending around said shoe sole on each side to a

position adjacent said heel, said border including a side flange, a top flange and a bottom flange, said side flange engaging the outer side surface of said sole and said top flange engaging the upper surface of said sole and said lower flange engaging the lower surface of said sole, means to secure said border in position on said sole, and a pressure device, said device comprising a flat member having a depression therein intermediate the length thereof, said member extending transversely of said sole and the ends of said member being positioned between said sole and said lower flange of said border, said depression of said member causing said sole to bulge inwardly.

3. In combination with a shoe including a sole and a heel, a border, said border extending around said shoe sole on each side to a position adjacent said heel, said border including a side flange, a top flange and a bottom flange, said side flange engaging the outer side surface of said sole and said top flange engaging the upper surface of said sole and said lower flange engaging the lower surface of said sole, means to secure said border in position on said sole, a plurality of spaced apertures in said lower flange and resilient pads positioned in certain of said apertures, and a pressure device, said device comprising a flat member having a depression therein intermediate the length thereof, said member extending transversely of said sole and the ends of said member being positioned between said sole and said lower flange of said border, said depression of said member causing said sole to bulge inwardly.

4. In combination with a shoe including a sole, a border, means to secure said border in position on the edge of said sole, and means associated with said border to cause an inward bulging of the bottom of said sole, said bulging occurring at a location spaced from said border.

5. In combination with a shoe including a sole, a pressure applying device, said device including a housing positioned on the outer surface of said sole adjacent the arch of said shoe, means engaging the top edges and sides of the sole to secure said housing to said shoe, an expansion member positioned in said housing and having a portion engaging said sole, and means to expand said member to cause said portion to bulge said sole inwardly.

6. The combination of a shoe including a sole and a heel, and a pressure device, said device comprising a flat member having a protuberance thereon intermediate the length thereof, said member extending transversely of said sole and the ends of said member being positioned adjacent to said sole, and means to secure said device in place, said protuberance causing said sole to bulge inwardly.

7. The combination of a shoe including a sole and a heel, and a pressure device, said device being positioned under the arch of said shoe and comprising a housing having 5 side flanges positioned adjacent said sole, an expansion member positioned in said housing, said expansion member including a lower section and an upper section, a tapered annular threaded recess in said lower and upper 10 sections, a tapered threaded bolt positioned in said recess, said bolt when rotated in one direction being adapted to move said upper section away from said lower section to bulge said sole inwardly, and means to secure said 15 housing in place.

In testimony whereof, I hereunto affix my signature.

EDWARD E. DETTELBACH.
